To all whom it may concern:

Be it known that I, ALFRED HEALD, of the city and county of Philadelphia, State of Pennsylvania, have invented a Design for a Carpet-Pattern, (G,) of which the following is a specification:

My design, which is clearly illustrated by the figure in the accompanying drawing, is entirely of a foliated character, the principal members of the pattern being stems *a*, bunches of flowers, leaves and stems *b*, small oblong ornaments *c*, and drooping leaves *d*, all arranged in the manner clearly shown in the draw-

ing, so as to produce a general, light, and pleasing effect.

Irrespective of the colors employed, I claim—
The design for a carpet-pattern, substantially as described, and as represented in and by the accompanying drawing.

In testimony whereof I have signed my name to this specification in the presence of two subscribing witnesses.

ALFRED HEALD.
